UNITED STATES PATENT OFFICE.

WILLIAM T. GELTZ, OF CLEVELAND, OHIO.

WORKMAN'S TIME-RECORDER.

1,217,589.

Specification of Letters Patent. Patented Feb. 27, 1917.

Application filed November 18, 1915. Serial No. 62,220.

To all whom it may concern:

Be it known that I, WILLIAM T. GELTZ, a citizen of the United States, residing at Cleveland, in the county of Cuyahoga and State of Ohio, have invented certain new and useful Improvements in Workmen's Time-Recorders, of which the following is a specification.

This invention relates to workmen's time recorders of that type in which "in" and "out" records are made on individual cards by means of time-operated printing wheels or the like, and more particularly to that class thereof in which the card guide or holder is shifted by means of a hand lever to receive marks in the respective positions, said lever in the present case also being operable to effect the printing operation, both the shifting and the printing being therefore done by a single lever. This lever is movable in one direction for the shift and in another direction at an angle to the former for the printing.

The invention also provides means for clipping the record card after each "out" operation, by means of the lever, and for ringing the alarm bell at each operation. The card is clipped in order that it may be located in proper positions for successive registrations.

Although illustrated in connection with a machine in which the card is inserted vertically, the invention may be applied with slight modification to a machine in which the card is inserted horizontally or otherwise; and no limitation is implied with respect to the particular use or arrangement of the device to be described.

In the accompanying drawings, Fig. 1 is a top plan view, partly in section, of the mechanism.

Fig. 2 is a vertical sectional elevation.

Fig. 3 is a front elevation of the record card receiver.

Fig. 4 is a detail of the cutting device.

Fig. 5 is a section on the line 5-5 of Fig. 3.

Referring specifically to the drawings, 1 indicates a face plate on the casing C which may be attached to or form part of the recorder casing. This face plate has a cross slot 60 with two vertical slots 61 at opposite ends thereof. A finger lever 2 is movable in the cross slot to position the card receiver for either "in" or "out" registrations, and is movable in the vertical slots

to operate the printing device. This lever has a shield 3 of sufficient size to cover the slots in all positions and prevent access to the inner mechanism. The lever turns horizontally on a vertical guide rod or shaft 4, by means of a sleeve 6 loose on said shaft, and turns vertically on a pivot pin 5 which extends through a boss on said sleeve and through a yoke 2 which incloses the upper end of the sleeve and forms part of the lever. The inner end of the lever terminates in a pin 8 which extends through a hole 9 in the margin or edge of a laterally shiftable card receiver 7, which slides on horizontal guide rods 70 and projects at its upper end through the casing where it has a flared mouth 36 to facilitate the insertion of a card, and a plate 37 which slides under guide plates 38 fastened to the outside of the casing. The plate 37 is sufficiently long to cover the opening through the casing in all positions. The card receiver has an opening 35 through its walls to permit the imprint of the time printing wheel 80 by impact of a hammer 22, as well as the operation of the notching device to be described.

By shifting the lever 2 to the right or left the card holder 7 is also shifted laterally to register the printing device with "in" or "out" positions.

The sleeve 6 is slidable up and down, as well as being rotatable, on the rod or shaft 4. By pressing the lever 2 down into either slot 61 it turns on the pin 8 bearing against the edge of the hole 9 as a fulcrum, and the sleeve 6 is slid down on the shaft 4, compressing the spring 10 coiled around the shaft between a bracket 90 and the sleeve. The sleeve 6 has at its lower end a collar 15 adapted to strike the end of a pawl 16 which is pivoted at 17 to an arm 18 on a rock shaft 20 to which a hammer 22 is fastened. A spring 19 bears against the end of the pawl 16 and permits back-slip of the collar 15 on the up-stroke thereof, the collar being inclined for this purpose. On the down stroke, the collar engages the pawl and strips or rocks the shaft 20 against the tension of a spring 21 fastened thereto, and when the collar passes the pawl the spring causes a rebound or return of the shaft 20, with a quick action, causing the hammer to strike the back of the card which receives a printing time impression from the type wheel 80. When the lever 2 is released the spring 10 returns the sleeve 6 and collar 15 to upper

position. The return snap or movement of the shaft 20 also causes the bell hammer 23 to strike the bell 24 and ring the alarm. The screws 26, which hold the end of the 5 spring 21 between the forks 25 of a supporting bracket, enable the spring and rock shaft to be adjusted to proper or exact position to give the stroke.

The notching device, for cutting a notch 10 in the lower side edge or corner of the card, comprises a lever 14 projecting from a sleeve 14^a which is loose on the shaft 20. This lever carries at its upper end a roller 12 on a pin 13, the roller being in contact with a conical 15 cam 11 on the sleeve 6. This lever is adapted to press against a stud 28 carried by a spring 27 fastened to the card receiver 7, and the upper end 40 of the spring carries a shear member 28^a which co-operates with the 20 cutting edges 39 around an opening in the wall of the card receiver 7. A pin 41 projects from the spring across the receiver slot and acts as a stop for the notched edge of the card when it is inserted in the receiver 7. 25 The shaft 20 is mounted in bearings 30, and a spring 29 is connected between one of the bearings and the sleeve 14^a, and normally holds the lever 14 in retracted position. When by means of the lever 2 the card receiver is shifted to the "out" position the stud 28 is shifted to position in line with or opposite the lever 14, and when said lever 2 is depressed, the cam 11 bearing against the 30 wheel 12 turns said lever 14 which presses against the stud 28 and operates the shear to cut a notch in the edge of the card resting against the pin 41, so that at the next operation, the card will occupy a lower position in the receiver, thereby varying the location 35 of the printed record. This shearing operation occurs only at each final "out" operation. When the receiver is in the "in" position, as shown in Fig. 1, the stud 28 does not register with the lever 14 and consequently, 40 although the lever swings, the shear is not operated. When after each operation of the lever 2 it is lifted by the spring 10 the cam 11 lifts with the sleeve, and the spring 29 returns the lever 14.

50 It will be seen that by means of a single lever 2 the card receiver is shifted, the impression is given, the shear is operated (under "out" conditions), and the bell is sounded.

55 The entire mechanism is assembled in a single casing which can be readily attached to or detached from the main part of the recorder, and it is independent of the time mechanism. Although the mechanism illustrated gives only two registrations across a card, it may be modified to provide for additional registrations, by increasing the possible range or lateral movement of the lever 2.

60 Various other modifications may be made 65 to adapt the mechanism for vertical or hori-

zontal arrangement, and for various arrangements or locations of the recorder impressions, and no limitation in this respect is implied.

What I claim as new is:

1. In a time recorder, the combination of 70 a shifting card receiver, a printing device, a guide rod, a pivoted and sliding sleeve on said rod and adapted to operate said device, and a single operating lever operatively connected to said receiver and to said sleeve and adapted to both shift said receiver and actuate said device.

2. In a time recorder, the combination of 75 a shifting card receiver, a printing device, a card cutting device, and a single lever operatively connected to each of said devices and the receiver, for operating the former and shifting the latter.

3. In a time recorder, the combination of 80 a shifting card receiver, a printing device, a card cutter device, an alarm device, a single operating lever, the means operatively connecting said lever to each of said devices, whereby they may be operated by said lever. 85

4. In a time recorder, the combination of 90 a shifting card receiver, a card cutting device, a lever connected to said receiver for shifting the same, and means connecting said lever and said card cutting device in 95 one position of the lever, for operating said device by said lever when the latter is in said position.

5. In a time recorder, the combination of 100 a printing mechanism including a pivoted hammer, a spring connected thereto, a pawl connected to the hammer, a lever, and a sliding member connected to the lever and movable in one direction to engage the pawl and retract the hammer against the tension 105 of the spring, and to release the pawl on further movement, in said direction, whereby the spring will advance the hammer, said pawl being yieldable in one direction, to permit back slip of the said member. 110

6. In a time recorder, the combination of 115 a guide rod, a sleeve slidable thereon, an operating handle connected to the sleeve, a spring-actuated printing hammer, and means actuated by movement of the sleeve to operate the hammer.

7. In a time recorder, the combination of 120 a guide rod, a sleeve slidable thereon, an operating handle connected to the sleeve, a spring-actuated printing hammer, and means actuated by movement of the sleeve to operate the hammer, said means including a pawl projecting into the path of movement of the sleeve and operatively connected to the hammer.

8. In a time recorder, the combination of 125 a printing mechanism including a hammer, a spring actuated rock shaft on which the hammer is mounted, a pawl connected to said shaft, and a tripping device engageable 130

with said pawl to rock the shaft against the tension of the spring and release the same to permit the stroke of the hammer, said tripping device including a rotatable and sliding member and an operating lever connected thereto.

5 9. In a time recorder, the combination of a shifting card receiver, a slide, a guide on which said slide is pivotally and slidably mounted, a lever pivoted to the slide and engaging said receiver, to shift the same when said lever and slide are turned on the guide, a printing mechanism, and means actuated by the slide to operate said printing mechanism when the slide is reciprocated on the guide.

10 10. In a time recorder, the combination of a shifting card receiver, a guide rod, a sleeve slidably and rotatably mounted on the rod, a lever articulated to the sleeve and pivotally connected to said receiver and adapted to shift the receiver when turned on said rod as a fulcrum, and to reciprocate the sleeve on said rod when turned on the receiver as a fulcrum, a printing mechanism for the card, and means actuated by reciprocation of the sleeve on the rod to operate said mechanism.

15 11. In a time recorder, the combination of a laterally shifting card receiver, a movable cutting member carried thereby and operating across said receiver to cut a card therein, a lever engageable with said member when the receiver is in one position, to effect the cutting operation, and means to operate said lever.

12. In a time recorder, the combination of a shifting card receiver, a movable cutting member carried thereby and operating across said receiver to cut a card therein, 40 a lever engageable with said member when the receiver is in one position, to effect the cutting operation, and means to operate said lever, said means including a sliding cam bearing against said lever.

45 13. In a time recorder, the combination of a laterally shifting card receiver, a printing device including a hammer, a card cutting device including a lever, a single operating lever connected to the receiver and movable in one direction to shift the receiver, a guide rod, and a sleeve rotatable and slidable on the rod and connected to the lever, said sleeve having a tripping device for operating the hammer and a cam engageable with the lever of the cutting device for operating the latter.

50 14. In a time recorder, the combination of a guide, a sleeve slidable and rotatable thereon, an operating handle connected to the sleeve, to turn or slide the same, a spring-actuated printing hammer, and means actuated by the sliding movement of the sleeve, in any of its turned positions, to operate the hammer.

55 In testimony whereof, I do affix my signature in presence of two witnesses.

60 WILLIAM T. GELTZ.
